UNITED STATES PATENT OFFICE.

MICHAEL L. SCANLON, OF CLEVELAND, OHIO.

COMBINATION COAL AND GAS STOVE OR RANGE.

1,121,207.

Specification of Letters Patent. Patented Dec. 15, 1914.

Application filed August 11, 1913. Serial No. 784,196.

To all whom it may concern:

Be it known that I, MICHAEL L. SCANLON, a citizen of the United States, residing at Cleveland, in the county of Cuyahoga and State of Ohio, have invented a new and useful Combination Coal and Gas Stove or Range, of which the following is a specification.

The present invention appertains generally to stoves and ranges, and relates more particularly to a novel and improved combination coal and gas stove or range.

It is the object of the present invention to provide a unique stove or range construction, which shall permit of the consumption of both solid and gaseous fuels, both for heating the top of the stove and for heating the oven or baking chamber.

Among its specific objects, the present invention aims to provide a novel means for heating and ventilating the oven or baking chamber.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:—

Figure 1 is a perspective view of the improved stove or range. Fig. 2 is a top or plan view of the stove with the top removed. Fig. 3 is a vertical section taken approximately on the line 3—3 of Fig. 2, parts being shown in full. Fig. 4 is a reduced horizontal section taken on the line 4—4 of Fig. 3. Fig. 5 is a sectional detail taken approximately on the line 5—5 of Fig. 3, parts being shown in full. Fig. 6 is a sectional detail taken on the line 6—6 of Fig. 2. Figs. 7 and 8 are sectional views taken on the lines 7—7 and 8—8 of Fig. 6 respectively. Fig. 9 illustrates the damper controlling the passage leading from the upper flue or secondary combustion chamber to the up-draft flue or outlet, side and top views of the damper being included in the figure. Fig. 10 is a perspec-

tive view of the damper actuating rod. Fig. 11 is a perspective view of one of the lids. Fig. 12 is a horizontal section taken through the stove, on a reduced scale, illustrating a modified form of burner for the bottom of the oven or baking chamber. Fig. 13 is a sectional detail illustrating the carriers swung to bring the closure plate over the channel.

Referring specifically to the drawings, the stove or range comprises a suitable casing embodying the front wall 1, the end walls 2 and 3, the back wall 4, the bottom 5, and the top 6, which may be assembled in any well known manner. Between the front and back walls, are secured the upright partitions 7 and 8, and the horizontal partitions 9 and 10, forming the oven or baking chamber. The partition 7 forms the left hand end of the oven and coöperates with the end 3 of the casing to provide the fire box and ash pit, a grate 11 being supported between the partition 7 and the end 3 of the casing, as is customary. The front wall 1 is also provided with the parts 11^a and 11^b leading to the fire box and ash pit, respectively, and is further provided with a door 12 for normally closing the oven or baking chamber. The upper horizontal partition 9 forming the top of the oven coöperates with the top 6 of the casing to define the upper horizontal flue or secondary combustion chamber 13, leading from the fire box to the down-draft flue 14 defined between the partition 8 and the end 2 of the casing. The down draft flue 14 leads to the lower horizontal flue 15 defined between the bottom 10 of the oven and the bottom 5 of the stove casing. The top of the casing is provided with a suitable number of openings, as usual, which are normally closed by the lids or covers 16, and an updraft flue 17 is attached to the back of the stove casing, and has the collar 17^a at its upper end for the attachment of the stove pipe. The back of the casing is provided with the openings 18 and 19 leading from the lower flue 15 and the upper flue 13, respectively, to the up-draft flue 17. The front wall 1 of the stove casing is also preferably provided with a clean-out door 20 communicating with the lower flue 15, and a damper 21 is provided for the opening 19 in order to control the draft, it being noted that when the damper 21 is open, the products of combustion will pass directly up the flue 17 to the chimney, while

when the damper 21 is closed, the products of combustion will be constrained to pass around the oven, and up the flue 17 from the lower flue 15, in the manner of a downdraft oven.

The foregoing structure is common in stoves and ranges, and is well understood in the art, so that a further description thereof is not necessary.

In carrying out the present invention, a number of gas burners 23 are disposed upon the top 9 of the oven underneath certain of the openings in the top of the casing, a suitable gas supply pipe 24 being arranged at the end 2 of the casing, and having the upper branches 24^a extending through the end 2 of the casing and leading to the several burners 23. Suitable valves may be provided for the branches 24^a to control the admission of the gaseous fuel to the burners 23, these valves being well known and not being illustrated. It is evident that when the respective lids 16 are removed, the burners 23 will be exposed, and the same may be employed for cooking or other purposes, as will be apparent.

In order to protect the burners 23 when coal or other solid fuel is employed, the lids 16 above the several burners 23, are provided with the depending aprons 25 adapted to surround or house the burners 23, when the lids are in place, the aprons 25 being provided with the notches 26 for receiving the branches 24^a. It will thus be obvious that when the lids are positioned in the top of the stove casing, to permit coal or similar fuel to be burned within the fire box, the aprons 25 will prevent the products of combustion from injuring the gas burners 23.

Coming to the means for heating the oven or baking chamber by gaseous fuel, the same embodies the following essentials. The forward portion of the partition 10 of the oven is depressed to form a gutter or channel 27 adjoining the front of the stove casing, and the front of the casing is provided with a horizontal series of apertures or vent openings 28 in advance of the channel 27, a sliding damper 29 being mounted on the inner side of the front 1 of the casing and having apertures or openings adapted to be brought into and out of registration with the apertures 28. A gas burner embodying a straight tapered pipe 31 having a series of apertures along its top, is disposed along the rear or back wall of the channel or gutter 27, the supply pipe 24 having a branch 30 passing through the casing and the partition 8 and entering the respective end of the channel 27 so as to receive the largest or open end of the burner 31, as seen in Fig. 5. The other end or tip of the burner 31 is supported by a suitable saddle 32 secured to the partition 7 within the respective end of the channel 27.

A false bottom 33 is provided for the oven, and is spaced slightly above the bottom of the oven, the false bottom 33 being removably supported on cleats 34 secured to the partitions or oven sides 7 and 8. The lower face 70 of the false bottom 33 is preferably supplied with a layer or layers of asbestos or the like, and the rear end of the false bottom 33 is preferably inserted underneath lugs or studs 35 carried by the partitions 7 and 8 adjoining the back of the casing. The lugs 35 retain the rear end of the false bottom on the cleats 34, and permit the forward end of the false bottom 33 to swing upwardly when withdrawn, as will hereinafter appear. The 80 false bottom 33 is provided with a series of notches 36 along its inner end, and with a series of apertures 37 along each side edge, to provide vents leading from below the false bottom 33 to the oven or baking chamber 85 proper, it being noted that the notches 36 and apertures 37 are disposed adjoining the back and sides of the oven or baking chamber, so that the products of combustion or gases, will proceed rearwardly from the 90 burners 31 under the false bottom 33 and then upwardly through the openings 36 and 37.

The space between the bottom 10 of the oven and the false bottom 33 is normally 95 closed by means of a plate 38 secured to the forward ends of carriers 39 pivoted to the partitions or oven sides 7 and 8 immediately above the ends of the burner channel or gutter 27 at the forward end of the oven bottom. 100 The plate 38 is normally adapted to stand vertically between the lower edge of the door opening of the oven or the forward side of the channel, and the forward end of the false bottom 33 which terminates adjoining the door 12. The carriers 39 are arcuate or curved, and have their intermediate portions pivoted to the partitions or side walls of the oven, a rounded rib 40 being secured to the lower face of the false bottom 33 along its forward end and having portions normally seating within the upper curved recesses of the carriers 39 to retain the carriers in position, and to consequently maintain the closure plate 38 in proper position. It is evident that the vessels or objects inserted into the oven, may be readily seated upon the false bottom 33, which is heated by means of the burner 31. It is also preferable to provide a gas burner 41 below the top of the oven, which is connected with the supply pipe 24 by means of the branch 41^a. This burner is intended to radiate the heat downwardly for the purpose of broiling, baking or the like, as is well known.

The back 4 of the stove casing is provided with a series of apertures 42 directly below the rear edge of the partition 9 or top of the oven, which will establish communication from the oven into the flue 17, a slid-

ing damper 43 being carried by the back 4 in rear of the aperture 42 and being provided with apertures adapted to be brought into and out of registration with the apertures 42.

The dampers 21 and 43 are controlled by means of a vertical damper rod 22, which is journaled slidably through the top 8 of the stove casing, and through a rearwardly projecting ear 44 carried by the back of the casing intermediate the dampers 21 and 43. The upper end of the rod 22 is formed into a crank or handle 45 for convenience in manipulating the damper rod, and the lower end or extremity of the damper rod is reduced in diameter, as at 46, and has a ward 47. The damper 43 is provided at one end with a pair of parallel ears or lugs 48, which normally receive the lower end of the thickest portion or body of the damper rod 22, to constrain the damper 43 against sliding; the ward 47 being normally disposed below the ears 48, in order that when the damper rod 22 is oscillated in depressed condition, the ward 47 will not tend to slide or actuate the damper 43. The damper rod 22 is located at one side of the opening 19 and the apertures 42, and is operatively connected with the respective ends of the dampers 21 and 43.

The damper 21 is pivoted to the damper rod 22, the damper 21 and damper rod having a novel interengaging means, as will be presently described. The damper 21 is provided with the lower and upper tongues 49 and 50 projecting from its basal end, and has a tongue 51 intermediate the tongues 49 and 50. The tongues 49 and 50 are curved gently away from the plane of the damper 21, while the tongue 51 is bent back and curved in a direction reverse to the direction of curvature of the tongues 49 and 50, the tongues 49-50 and 51 coöperating to loosely embrace the damper rod 22. The lower tongue 49 is provided with an upper notch or cut away portion 52 at its free end, and the tongue 51 is provided with a similar notch or cut away portion 53.

The damper rod 22 is provided with a key or projection 54 between the tongues 49 and 50 of the damper 21, which key is adapted to engaging between the ends of the tongues 49 when the damper rod is depressed, in order that the key 54 will be engaged securely between the notch 52 of the tongue 49 and the free end of the tongue 51. Thus, when the damper rod is depressed, the key 54 in engaging between the end of the tongues 49 and 51, will constrain the damper 21 to swing with the damper rod, in order that the damper 21 may be swung to and from the opening 19 to control the draft, as above intimated. When the damper rod 22 is raised, the key 54 is adapted to swing into and out of the notch or cut away portion 53 of the tongue

51, without swinging the damper 21. It is to be observed that when the damper rod is elevated or raised, the ward 47 is designed to be drawn between the ears 48 of the damper 43, whereby the swinging movement of the damper rod in elevated position, will transmit a sliding motion to the damper 43 for controlling the passage of the gases from the oven through the apertures 43 to the updraft flue 17. It will thus be obvious, that when the damper rod is depressed, the same is adapted to actuate the damper 21, while when the damper rod is elevated, the damper 21 will remain idle, while the damper 43 is adapted to be actuated through the medium of the damper rod.

For convenience in holding the damper 21 closed, especially when the damper 21 is idle, the lower edge of the damper 21 is provided with a notch or recess 55, which is adapted to engage over a lug or projection 56 carried by the back of the casing.

A cam 57 is carried by the top of the stove casing adjoining the crank 45 of the damper rod, upon which the crank 45 is adapted to ride, when the damper rod is elevated and rotated so as to move the damper 43 in such a direction as to open the apertures 42, the cam 57 being provided with a stop 57^a for limiting the movement of the damper rod. Thus, when the damper rod is elevated and swung so as to open the apertures 42, the crank 45 will engage over the cam 57, and consequently, the damper rod cannot be depressed until swung to such a position as to slide the damper 43 to normal closed position.

From the foregoing, taken in connection with the drawings, it will be evident that the present stove or range may be employed for burning coal or other solid fuel, the use of coal or solid fuel being clearly apparent without lengthy description. It is evident, that when coal or other solid fuel is employed, that the damper 43 will be closed, as well as the damper 29, to seal the oven or baking chamber, and that the damper 21 may be opened or closed at will, through the medium of the damper rod, without affecting the closed position of the damper 43. Should it be desired to remove the false bottom 33, when coal is employed for fuel, this may readily be accomplished, by sliding the false bottom 33 outwardly, and the rib being moved outwardly will cause the carriers 39 to be so swung, as to raise the forward end of the false bottom 33 as it is being withdrawn, the closure plate 38 swinging downwardly over the gutter 27 so as to partly or completely close the same. Conversely, when the false bottom 33 is inserted, the carriers 39 will be engaged by the rib 40 and will be swung so as to bring the closure plate 38 to normal position between the forward end of

the false bottom 33 and the lower edge of the door opening of the oven. Thus, when the false bottom 33 is inserted, the oven may be heated from below by the burner 31, and the closure plate 38 will prevent the escape of the gases through the forward end of the space between the false bottom 33 and the bottom 10 of the oven. In this manner, when the oven is heated by the gas burner 31, the forward end of the combustion chamber below the false bottom 33 will be closed by the plate 38. On the other hand, when the false bottom 33 is removed, to enable the oven to be heated by coal or similar fuel, as usual, the closure plate 38 will be swung over the channel 32, to close the said channel, and to coöperate with the forward portion of the oven bottom 10 for supporting the baking pans or other vessels thereon in a convenient manner and at the same time to render the burner 31 inoperative.

When gaseous fuel is employed, the burners 23 may be lighted for cooking and similar purposes, the lids 16 having been removed. The oven may be heated through the medium of the burner 31, as above described, the products of combustion passing from the burner 31 under the false bottom 33 and up through the rear portion of the false bottom to the baking chamber or oven proper, the passage of the products of combustion into the discharge flue 17 being controlled by the damper 43. This damper 43 may be readily slid by raising the damper rod 22 and then oscillating the same, as hereinbefore described. The admission of air into the oven may be regulated by the damper 29, this damper being ordinarily closed, as is preferable when the burner 31 is employed. It is to be noted that when the damper 29 is opened, the air will be admit-

ted into the channel or gutter 27 so as to approach the burner 31.

In Fig. 12, a modified form of burner is illustrated for use below the false bottom 33, this modified form of burner comprising an S-shaped pipe 31' having a series of apertures along its top and having one end offset to be inserted into the branch 30, similar to the burner 31. The burners 31 and 31' may be employed interchangeably, the burner 31 creating a larger flame which may be desirable at times. When the burner 31' is employed, the damper 29 is preferably opened to admit air to the burner 31', so as to promote combustion.

Having thus described the invention, what is claimed as new is—

In a stove, an oven having a burner channel at the forward end of its bottom, a removable false bottom slidably supported by the sides of the oven and having a lower rounded rib along its front end, carriers pivoted to the sides of the oven immediately above the channel and having upper curved recesses in which the said rib is seated when the false bottom is at normal position, a closure plate secured to the forward ends of the carriers to close the space between the front end of the false bottom and the forward side of the channel and to swing over the channel when the false bottom is withdrawn, the said rib serving to operate the carriers.

In testimony that I claim the foregoing as my own, I have hereto affixed my signature in the presence of two witnesses.

MICHAEL L. SCANLON.
